Inventor,
D. C. Pierce.

United States Patent Office.

D. C. PIERCE, OF CLAYTON, NEW YORK.

Letters Patent No. 99,346, dated February 1, 1870; antedated January 31, 1870.

IMPROVED RAILWAY-FROG.

The Schedule referred to in these Letters Patent and making part of the same.

To all whom it may concern:

Be it known that I, D. C. PIERCE, of Clayton, in the county of Jefferson, and State of New York, have invented certain new and useful Improvements in Railway-Frogs; and I do hereby declare that the following is a full, clear, and exact description thereof, reference being had to the accompanying drawings, making part of this specification, and to the letters of reference marked thereon, like letters indicating like parts wherever they occur.

To enable others skilled in the art to construct and use my invention, I will proceed to describe it.

My invention relates to railway-frogs, and consists in constructing them of an upper or face plate, with suitable openings through it, in which are inserted the frog-point and guard-rails, made of iron or steel, in such a manner as to be removable, and of a lower or base plate, so constructed that the face plate may be firmly secured to it, and so that an elastic material of any suitable kind may be interposed between the plates; and also in the novel construction and arrangement of end-pieces for connecting the frog with the track-rails.

In the drawings—

Figure 1 is a top plan view;

Figure 2 is an edge view; and

Figure 3 is a cross vertical section on the line $x-x$ of fig. 1.

In constructing my frog, I make an upper or face plate, C, out of suitable material, and of any size desired, and provide it with openings corresponding with the shape and size of the face of a frog-point, E, and guard-rails F, or of any other frog-point or guard-rails that may be required.

These frog-points and guard-rails I make of steel, with flanges *a* at their base, so as to give them a broad support, and then insert them through the under side of the face plate C, as clearly shown in figs. 1 and 3, interposing, at the same time, an elastic material, D, of wood, paper, or other suitable material, between the upper side of the flanges and the under side of the face plate, as shown in fig. 3.

I then make an under or base plate, A, of the same size and form with the face plate C, constructing it with a depression, *b*, on its upper face, for the insertion of any suitable elastic material, at shown in said fig. 3, and also with flanges G, for connecting it to the sleepers.

These plates, thus constructed, and with the frog-point and guard-rails inserted, I then fasten together with screw-bolts and nuts *d*, having first interposed the elastic material proposed to be used. This elastic material, I so place and arrange as to form the bearing, both on the upper and lower sides of the flanges of the frog-point and guard-rails, as well as between the plates themselves, as clearly shown in fig. 3.

The ends of my frog, I provide with pieces B, having a notch or shoulder, C, on their upper inner side, for a projection of the base plate A to bear upon, as shown in fig. 2, and also for the flanges of the guard-

rails at one end, and the flanges of the frog at the other, to extend over and bear upon.

These end-pieces B are attached to the ends of the frog, just in front of one of the sleepers, and so that its highest upper face may come under the end of the upper plate C, as shown in fig. 1.

If desired, these end-pieces B may have their sides extended up with lugs *e*, formed so as to clasp on the upper side of the face plate C, as shown in the same figure.

My frog, thus constructed, has many advantages. Being made of two plates, it can be conveniently taken apart for the removal or renewal of the frog-point and guard-rails, or any one of them. To do this, it is only necessary to unscrew the nut, as shown in fig. 1, and lift up the face plate, when the frog-point or guard-rails can be taken out, or either of them, and others put in their place; and in the same manner the interposed elastic material can be removed, and other material put in its place, if desired.

As is well-known, railway-frogs, as ordinarily constructed, wear out rapidly, and are a source of heavy expense to railway companies; but as my frog-points and guard-rails are made of steel, and also made removable, it is evident that my improved frog possesses many advantages over the old frog, and can be used at a great saving of expense in the long run, as the frog-point and rails can be removed as often as desired.

By the use of the end-pieces B, constructed and connected to the frog as described above, it will be seen that the ends of the track-rails and the ends of the guard-rails, or the end of the frog-point, with which they connect, are kept in such position that their upper surfaces are always in the same horizontal plane, so that there is little or no jamming of these ends by the wheels of the passing locomotive, car, or train.

While my railway-frog is constructed of two plates, an upper and a lower, it is evident that the principal object of the lower plate is to supply a bearing or support for the frog-points and guard-rails, and that other bearings might be substituted for the plate.

Having thus described my invention,

What I claim, is—

1. A railway-frog, consisting of the plates A and C, frog-point E, guard-rails F, and elastic material D, all constructed and arranged substantially as herein described.

2. In combination with a railway-frog, as herein described, the end-pieces B, constructed and arranged substantially as and for the purpose set forth.

3. In the construction of railway-frogs, inserting the frog-points and guard-rails, provided with flanges at their base, through the frog-plate, substantially as herein described and for the purpose set forth.

D. C. PIERCE.
